UNITED STATES PATENT OFFICE.

EDWIN J. TOOF, OF NEW HAVEN, CONNECTICUT, ASSIGNOR TO THE
EDWIN J. TOOF COMPANY, OF NEW HAVEN, CONNECTICUT, A COR-
PORATION OF NEW JERSEY.

SEWING-MACHINE.

SPECIFICATION forming part of Letters Patent No. 761,558, dated May 31, 1904.

Application filed June 26, 1889. Serial No. 315,667. (No model.)

To all whom it may concern:

Be it known that I, EDWIN J. TOOF, a citizen of the United States, and a resident of the city of New Haven, county of New Haven, and State 5 of Connecticut, have invented new and useful Improvements in Sewing-Machines, of which the following is a specification.

My invention has for its object to provide a sewing-machine that may be used for making either a lock-stitch or a chain-stitch.

In carrying the invention into effect I provide a lock-stitch sewing-machine of ordinary construction with a chain-stitch device which will be inoperative during the operation of 15 the machine in making lock-strokes, but which may be rendered operative to adapt the machine for making chain-strokes whenever it is so desired, such change in the operation of the machine for the formation of the different 20 stitches being effected without the addition or substitution of any parts.

Referring to the accompanying drawings, forming part of this specification, Figure 1 is a front end elevation, partly broken away, of 25 a sewing-machine embodying my invention. Fig. 2 is an under side view of the same, on a reduced scale. Figs. 3, 4, 5, and 6 are detail views illustrating the operation of my invention, and Figs. 7, 8, and 9 are detail views to 30 be hereinafter referred to.

Similar reference characters designate like parts in the several figures of the drawings.

My invention is herein shown as applied to a "Standard" lock-stitch sewing-machine of 35 usual construction and operation, the same embodying the work-plate A, the rotary driving-shaft B, mounted in suitable bearings at the under side of said work-plate, the rotary loop-taker or shuttle C, actuated from said 40 driving-shaft, and the vertically-reciprocating needle α' .

The chain-stitch device embodying my invention, as herein shown, comprises a loop-holder E, having a forked or slotted end e. 45 This loop-holder is adapted to be actuated to have a reciprocating movement and coöperate with the needle and the loop-taker in the formation of a chain-stitch in a manner as fol-

lows: The machine being set in motion to reciprocate the needle and rotate the loop-taker, 50 the said needle descends, and as it rises it throws out a loop of thread α^2 , which is seized by the beak e of the loop-taker, as shown in Fig. 3, and as said loop-taker continues its rotation and the needle continues to rise the 55 said loop is carried around the body of the loop-taker in the usual manner, as indicated in Fig. 4, until said loop-taker reaches the position shown in Fig. 5, when the loop, having been partially drawn up by the take-up, will be 60 engaged by the loop-holder E and held thereby in an open or distended condition across the path of movement of the needle, the said loop-holder having been moved forward to such loop engaging and holding position during the described rotation of the loop-taker. 65 At this time in the operation of the parts the needle will descend into the space between the two prongs at the forked end of the loop-holder and carry its thread through the distended loop held thereby, as shown in Fig. 6. As the parts now continue their operation 70 the loop-taker will be moved back from its holding position, so as to cast off the loop held thereby, as shown in Fig. 3, and the second 75 loop thrown out by the needle will be seized by the loop-taker beak and drawn through the first loop, which latter is subsequently drawn up and tightened in the work in the usual manner. When the thread-loop is engaged by the loop-holder subsequent to its release by the loop-taker beak, as shown in Fig. 5, it is desirable that the loop should be 80 positively positioned in its open or distended condition across the path of the needle, so as to insure its being entered by the latter, and thereby avoid the skipping of stitches. To provide for such positioning of the loop, the loop-holder E is provided with a transversely-arranged notch e' at its under side and in a 85 position forward of the rear end of the space or slot between the prongs of the loop-holder into which the thread-loop is received and properly positioned, as most clearly shown in Fig. 9. The loop-holder may be actuated to 90 have a forward-and-backward or reciprocating

ing movement to coöperate with the needle and the loop-taker in the formation of a chain-stitch in the manner described by any suitable means, the means provided for such purpose, as herein shown, comprising a lever D, pivoted at one end to the under side of the work-plate at d and at its opposite end having the said loop-holder E attached thereto and a cam F on the shaft B, against which the said lever is operatively held by a suitable spring, such as G. With these parts rotation of the cam F will vibrate the lever D, which in turn will impart the desired reciprocating movement to the loop-holder, as before described.

15 When it is desired to employ the machine for lock-stitch sewing, the loop-holder E should be held in a stationary or inoperative position, and as a simple and effective means for doing this a locking-lever H is pivoted to the under side of the work-plate at h' and provided with a projection h thereon for coöperating with a cam-surface d' at the free end of the lever D to draw the latter away from operative engagement with the cam F, as indicated by dotted lines in Fig. 2, and hold the same in such position until it is again desired to employ the machine for chain-stitch sewing, when it will only be necessary to swing the locking-lever H back from its position of holding engagement with the lever D, whereupon the latter will be automatically returned to its operative position under the action of the spring G.

20 When the machine is used for lock-stitch sewing, the loop-taker will contain the usual bobbin carrying the underthread-supply; but when the machine is used for chain-stitch sewing, the said underthread-supply is unnecessary, and therefore the bobbin containing the same will preferably be removed from the loop-taker, the bobbin-case I, however, being employed, so as to present a smooth surface at the face side of the loop-taker for the free and unobstructed passage of the front side of the thread-loop thereover. Aside from this insertion and removal of the bobbin into and from the loop-taker the only change necessary to adapt the machine for either chain-stitch sewing or lock-stitch sewing is 25 the mere shifting of the loop-holder to and from its operative position, as described.

What I claim is—

1. In a sewing-machine, the combination with the needle and a loop-taker, of a loop-holder operative for receiving the needle-thread loop after it has been released by the loop-taker and holding the same in an open or distended condition across the path of the needle and thereafter releasing the loop subsequent to the passage thereinto of the needle, the said loop-holder being provided with a forked or slotted end for the passage of the needle into the loop held thereby, and means for actuating the loop-holder.

2. In a sewing-machine, the combination 65 with the needle and a loop-taker, of a loop-holder independent of the loop-taker and operative for receiving the needle-thread loop after it has been released by the loop-taker and holding the same in an open or distended 70 condition across the path of the needle and thereafter releasing the loop subsequent to the passage thereinto of the needle, the said loop-holder being provided with a forked or slotted end for the passage of the needle into 75 the loop held thereby, and means for actuating the loop-holder.

3. In a sewing-machine, the combination, 80 with the needle and a loop-taker, of a reciprocating loop-holder for receiving the needle-thread loop after it has been released by the loop-taker and holding the same in an open or distended condition across the path of the needle, said loop-holder being provided with a forked or slotted end for the passage of the 85 needle into the loop held thereby, and means for actuating the loop-holder.

4. In a sewing-machine, the combination, 90 with the needle and a loop-taker, of a reciprocating loop-holder for receiving the needle-thread loop after it has been released by the loop-taker and holding the same in an open or distended condition across the path of the needle, said loop-holder being provided with loop-positioning means and with a forked or 95 slotted end for the passage of the needle into the loop held thereby, and means for actuating the loop-holder.

5. In a sewing-machine, the combination, 100 with the needle and a loop-taker, of a reciprocating loop-holder for receiving the needle-thread loop after it has been released by the loop-taker and holding the same in an open or distended condition across the path of the needle, said loop-holder being provided with 105 loop-positioning means at its under side and with a forked or slotted end for the passage of the needle into the loop held thereby, and means for actuating the loop-holder.

6. In a sewing-machine, the combination, 110 with the needle and a loop-taker, of a reciprocating loop-holder for receiving the needle-thread loop after it has been released by the loop-taker and holding the same in an open or distended condition across the path of the needle, said loop-holder being provided with 115 loop-positioning notch and with a forked or slotted end for the passage of the needle into the loop held thereby, and means for actuating the loop-holder.

7. In a sewing-machine, the combination, 120 with the needle and a loop-taker, of a reciprocating loop-holder for receiving the needle-thread loop after it has been released by the loop-taker and holding the same in an open or distended condition across the path of the needle, said loop-taker being provided with a 125 forked or slotted end for the passage of the needle into the loop held thereby.

needle into the loop held thereby, and means, including a vibrating lever, for actuating said loop-holder.

8. In a sewing-machine, the combination, 5 with the needle and a loop-taker, of a reciprocating loop-holder for receiving the needle-thread loop after it has been released by the loop-taker and holding the same in an open or distended condition across the path of the 10 needle, said loop-holder being provided with a forked or slotted end for the passage of the needle into the loop held thereby, and means including a cam and a lever for actuating said loop-holder.

- 15 9. In a sewing-machine, the combination,

with the needle and a loop-taker, of a reciprocating loop-holder for receiving the needle-thread loop after it has been released by the loop-taker and holding the same in an open or distended condition across the path of the 20 needle, said loop-holder being provided with a forked or slotted end for the passage of the needle into the loop held thereby, means for actuating the loop-holder, and means for holding the loop-holder in a stationary or inoperative 25 position, for the purpose set forth.

EDWIN J. TOOFS.
